[57] CLAIM

The ornamental design for a dispensing container for pharmaceutical tablets or the like, as shown and described.

DESCRIPTION

FIG. 1 is a top front perspective view of a dispensing container for pharmaceutical tablets or the like showing my new design;

FIG. 2 is an enlarged scale left-side elevation thereof; not disclosed in FIG. 1;

FIG. 3 is an enlarged scale rear elevation thereof; and

FIG. 4 is a bottom perspective view thereof.
